UNITED STATES PATENT OFFICE.

ALFRED SMALLWOOD, OF LONDON, ENGLAND.

FURNACE.

1,335,202.

Specification of Letters Patent. Patented Mar. 30, 1920.

Application filed July 31, 1918. Serial No. 247,642.

To all whom it may concern:

Be it known that I, ALFRED SMALLWOOD, a subject of the King of Great Britain, residing at 42 Hargrave Park, Highgate, London, N., in the county of Middlesex, England, metallurgist, have invented certain Improvements in or Relating to Furnaces, of which the following is a specification.

This invention comprises certain improvements in or relating to furnaces.

According to the present invention I combine a recuperator system for heating the air for combustion with a furnace in which the heat is applied to the goods by a series of individually regulable ports.

I advantageously provide a main primary combustion chamber which delivers to a heat flue or flues from which the distribution ports extend to the goods chamber. The recuperated air may be admitted to this combustion chamber at a position in the vicinity of its ingress extremity and also at a position substantially advanced along the combustion chamber having regard to the direction of flow of the contents therein.

In order that this invention may be clearly understood and readily carried into practice, reference may be had to the appended explanatory sheets of drawings, upon which:—

Figure 1 is a sectional side elevation of a furnace constructed according to the present invention.

Fig. 2 is a sectional end elevation of the furnace shown in Fig. 1, the plane of section being on line 1—2 of the figure last mentioned.

Fig. 3 is a sectional plan, the section being taken on line 3—4 of Fig. 2, and

Fig. 4 is a sectional elevation, the section being taken on line 5—6 of Fig. 1.

In a convenient embodiment of the present invention, the furnace comprises a structure involving a goods chamber *a* at the top extending substantially the full length of the structure, a longitudinal combustion chamber *b* disposed below said goods chamber, and also extending longitudinally of the structure, and two longitudinal heat flues *c* one on each side of said combustion chamber. From each heat flue to one side of the combustion chamber a series of ports *d* or conduits are provided at intervals along the length of the furnace. These ports are individually regulable by blocks or bungs

d' so that more or less heat can be supplied to any particular part of the goods chamber.

At one end *e* of the combustion chamber provision is incorporated for admitting gas for combustion. At its other end the combustion chamber communicates by lateral ports *f* with the heat flues *c*.

Below the combustion chamber and heat flues a recuperator system is incorporated. This may comprise three forward and return gas flues arranged at intervals in the width of the furnace. The goods chamber may communicate at its extremity *g* above the ingress extremity of the combustion chamber with two depending flues *h* which extend one at each side of the combustion chamber *b*. Below the combustion chamber these depending flues *h* adjoin a common space *i* which is in communication with the upper forwardly extending parts *j* of the three waste gas flues. These upper portions of the waste gas flues extend substantially the length of the furnace and adjoin the lower parts *k* of the waste gas flues which extend in a reverse direction to the front extremity of the furnace at which they adjoin a transverse flue *l* leading to the stack.

Located intermediately to the three gas flues are two forward and return air flues.

A transverse air inlet *m* is provided at the rear extremity of the furnace and from this air inlet the lower parts *n* of the two gas flues extend toward the front extremity of the furnace at positions between the waste gas flues *h* and at a point near to the transverse flue *l* leading to the stack said air flues returning at a higher level at *o*. At the rear of the furnace the air flues then pass into a series or layer of five hot air flues *p* located above the air and gas flues above described. These five air flues which may adjoin each other at the rear extremity of the recuperator system at *q* extend forwardly substantially the full length of the recuperator system to a point at which they enter a distributing chamber *r* for the hot air. From this distributing chamber two flues *s* extend one on each side toward the front of the furnaces and ultimately communicate by three ports *t* with each side of the ingress extremity of the combustion chamber *b*. Immediately in front of the said air ingress ports a baffle *u* may be provided in the combustion chamber. Two other conduits *v* extend from the hot air dis-

tributing chamber rearwardly a substantial part of the length of the combustion chamber and communicate by regulable hot air ports *w* one on each side with the combustion chamber *b* at a position near to its rear extremity.

Individually regulable heat distribution ports *x* may be provided across the rear end of the goods chamber. From the transverse 10 flues *f* by which communication is established between the combustion chamber *b* and the two flues *c* the ports *x* extend upwardly similar to the flues *d* but opening into the floor of the goods chamber.

15 What I claim as my invention and desire to secure by Letters Patent is:—

1. A furnace, including a goods chamber, a recuperator system adapted to receive the waste gases from said goods chamber, a combustion chamber, means for conducting air 20 for combustion through said recuperator system, heat flues extending along said com-

bustion chamber and interconnecting therewith, and individually regulable heat distributing ports extending from said flue to 25 the goods chamber.

2. A furnace, including a goods chamber, a recuperator system adapted to receive the waste gases from said goods chamber, a combustion chamber, means for conducting air 30 for combustion through said recuperator system, heat flues extending along said combustion chamber and interconnecting therewith, and individually regulable heat distributing ports extending from said flue to 35 the goods chamber, said recuperator system being arranged below said goods chamber.

In witness whereof I have hereunto set my hand in the presence of two witnesses.

ALFRED SMALLWOOD.

Witnesses:

ARTHUR H. BROWN,
EDGAR N. WHEELER.
